AUTOMATIC PRESSURE CONTROL OF SUGAR CANE MILLS

Filed Oct. 12, 1949

UNITED STATES PATENT OFFICE

2,691,339

AUTOMATIC PRESSURE CONTROL OF
SUGAR CANE MILLSJoseph N. Edwards, New Orleans, La., assignor to
Edwards Engineering Corporation, New Orleans, La., a corporation of Louisiana

Application October 12, 1949, Serial No. 120,838

1 Claim. (Cl. 100—170)

1 This invention relates to roll mills for crushing and pressing sugar cane to extract juice for use in the manufacture of raw sugar. In this type of mill the cane or other fibrous sugar-containing stalks are crushed and pressed by passing them over a pair of rolls and beneath an upper floating pressure roll having a tiltable axis and coacting with both of said pair to apply the desired crushing and juice extracting pressure to the cane. In the usual type of such mills the three rolls are connected by a pair of crown gears secured to the lower rolls, and both meshing with a gear on the upper roll so that the rolls and gears are connected in series, with power applied to one of the crown gears.

As the thickness of the mat of cane varies both across the width of the mat and lengthwise thereof, and as it is desired to maintain a substantially constant pressure on both ends of the upper roll, the latter is so mounted that it and its bearings may have vertical and tilting movements, in accordance with varying thicknesses of the mat of cane. To permit such vertical movement, and at the same time to maintain a yielding pressure on the upper roll, it has been proposed to apply downwardly acting fluid pressure on rams engaging the bearings of the upper roll. See for instance the patents to Nadler 1,978,218, Munson 2,101,266, and Schwarz 2,205,632.

As the rolls are connected at one end only by the gears, the resistance to rotation of the upper and floating roll causes the driving gear to exert a thrust on the geared end of the upper roll and lift the latter so that it exerts a lesser pressure on the mat at the geared end portion than on the other end.

The main object of the present invention is to provide means whereby the pressure on the mat is maintained substantially constant at the opposite ends of the upper or floating roll, and therefore, from a practical standpoint throughout the length of the roll. This is accomplished by providing independent means free of inertia and friction for automatically maintaining constant pressure on the rams, with the pressure at the gear driven end greater than at the opposite end, thereby to compensate for the upward thrust of the gears and to insure uniform pressure on the mat of cane.

A further object is to provide means whereby the pressure on the upper or floating roll remains substantially constant, irrespective of variations in the distance to which the upper roll lowers or is forced upwardly during the delivery of a mat of varying thickness.

2 A further object is to provide means whereby any desired difference in pressure may be maintained on the bearings at the ends of the upper or floating roll, and compensate for the upward thrust exerted by the crown gears.

A further object is to provide means for applying pressure on the upper or floating roll, and which is small, compact, safe, self-sealing, moisture and dust proof, and which does not require any maintenance.

In carrying out my invention I provide one or more hydro-pneumatic accumulators, each having a casing providing two chambers separated by a flexible and expandable diaphragm or bag, which prevents any mixing of the oil and gas. One of these contains a non-compressible liquid acting on the rams, and the other contains a gas under high pressure, providing a dynamic force on the diaphragm and on the liquid. The 15 chambers are of such relative sizes that normal variations in the volume of the liquid in the chambers, due to the raising and lowering of the rams, do not change the gas pressure to any substantial extent. Thus, the ends of the upper 20 roll may rise to different distances, and in doing so force different amounts of liquid into the corresponding liquid chambers and against substantially uniform pressure in the gas chambers; but substantially equal pressures will be exerted 25 on the opposite ends of the upper roll during normal bodily raising or lowering of the roll, or the raising of one end in respect to the other end.

The casings may be mounted on the rams with 30 their liquid chambers directly connected to the chambers of the rams, or they may be connected by small diameter flexible copper tubing, and thus the liquid and gas containing chambers may be conveniently located at any desired distance from the mill. There may be a large number of such casings grouped together and connected to tubing extending to the rams of different mills.

Where tubing is used, it may be of predetermined internal diameter and length, and the liquid may be of predetermined viscosity, so that momentary predetermined automatic increase in pressure on the rams may be obtained by the back pressure developed, thus compensating for 45 increase in the volume or consistency of the feed.

By means of the present invention it has been established that the extraction of sucrose from the cane is appreciably increased and the moisture content of the bagasse is lowered, due to the 50 freedom of vertical movement of the upper rolls or the ends thereof, and under uniform pressure;

the feed to the mill is more uniform with less choking; the power consumption is considerably lowered; and the general efficiency increased.

In the drawings:

Fig. 1 shows a conventional type of mill, and my improved means for controlling the pressure on the upper roll, and connected by tubing.

Fig. 2 is a diagrammatic view showing the conventional positioning of the rolls, and on a smaller scale, and

Fig. 3 shows a portion of a ram with the accumulator mounted directly thereon.

The common type of sugar mill shown in Fig. 1 has the usual pair of lower rolls 10 and 11 and a superposed or upper roll 12 having limited vertical movement in end frames supporting the rolls. The lower rolls are provided with spaced gears 13 which mesh with a gear 15 on the upper roll. Power is applied to rotate one of the rolls, and the gearing transmits the power to the other rolls. A mat of the cane or other material to be crushed and pressed to extract the juice is passed over the lower rolls and beneath the upper one, and the upper roll has limited vertical movement to permit the passage of a mat of varying thickness. These parts are all of the conventional type.

Means are provided for applying pressure to the bearing of the upper roll to crush the cane and force the juice therefrom. This means comprises a pair of rams, one at each end of the upper roll, and each including a vertically disposed cylinder 16 on the frame of the mill, and a piston 17 transmitting power to the upper side of a bearing 18 for the shaft 19 of the upper roll. A non-compressible fluid is maintained under pressure in the cylinder above the piston, to force the upper roll downwardly and thus apply the desired pressure on the mat as it passes over the lower rolls and beneath the upper one.

So far as concerns the parts above identified, they may be of any standard or suitable form, and do not, per se, constitute any novel part of my invention, which relates to the means employed for applying and maintaining substantially constant the pressure on the non-compressible liquid in the cylinders, thereby permitting but resisting the upward bodily movement or tilting of the roll by a mat the thickness of which may vary both across and along the same as the mat passes through the mill.

In order to apply the desired high hydrodynamic force, there is provided a hydraulic accumulator comprising a non-expansible casing 20 having a flexible and expansible diaphragm 21 separating the interior into two compartments, 22 and 23. The diaphragm is shown as a bag secured at its upper end to the casing where there is provided the conventional charging valve 27 which is normally closed to hold the gas in the bag under the desired high internal gas pressure. The casing has a check valve 25 at the opposite end, and normally held up and open by a spring, so that the liquid may freely flow in and out and against the high gas pressure in the bag. The top of the valve 25 is preferably flat, so that during shipment and storage, or in case there is a break in the tubing or other cause of leakage of liquid, the bag may expand under its high gas pressure and engage the valve to close it, and thus retain some liquid in the casing and prevent rupturing of the bag. The nipple 26 which provides the valve seat may be threaded for direct attachment to the ram, or welded or otherwise connected to small tubing through

which the non-compressible liquid may surge back and forth as the ram of the sugar mill raises and lowers by reason of variations in the mat.

As shown in Fig. 3, the nipple is threaded for direct attachment to the top of the ram, and in Fig. 1 it is connected to a flexible tube 26 leading to the ram of one of the cylinders. After the accumulator, precharged with gas through a valve 27, is attached directly or by tubing to the ram, the non-compressible liquid is pumped in past the valve 25, and until the bag has been contracted and the gas pressure increased to that desired for application to the ram. Thus, as an end of the upper roll 12 rises and lowers with variations in the thickness of the mat, the non-compressible liquid in the cylinder of the ram may surge to and from the liquid compartment 23 of the casing 20, but will remain under the desired high pressure applied by the gas acting through the flexible wall of the bag or diaphragm. As the volumetric capacity of the ram cylinder is small as compared to the volume of liquid in the accumulator, and the amount of gas available for contraction and expansion, the back and forth flow of the liquid through the tube 26 to the accumulator, and due to the raising and lowering of the upper roll, will effect only a minute change in the pressure exerted by the compressed gas when the accumulator is of large size compared to the volume of the cylinder of the ram. When a steady, substantially unchanging pressure is not essential and a momentary predetermined pressure increase is preferred, a tube 26 of very small diameter causes a resistance to the back and forth flow of the liquid of predetermined viscosity, and this resistance will vary with the length as well as the inside diameter of the tube. Thus, this diameter, the viscosity of the liquid, and the length of the tube may be predetermined, and back pressure developed in the tube will compensate for increase in the volume of the feed and its consistency.

In Fig. 1 there is shown an assembly in which any one of a plurality of accumulators may be operatively connected to the rams of a pair of mills. There are shown five of the accumulators A, B, C, D and E, and four of the tubes 26, 26a, 26b and 26c, the tubes 26 and 26a leading to the two rams of one mill, and the tubes 26b and 26c leading to the rams of another mill. Merely as an example, each accumulator may be of 10 gallon capacity for a 12 inch ram.

Each of the accumulators A and B may be operatively connected to either or both ends of one mill, and each of the accumulators C and D may be connected to either or both ends of the other mill. The accumulator E may serve as a spare, or to transfer liquid to any one of the other accumulators, or it may be removed and substituted for any one of the others.

In the arrangement shown, and with all of the valves 33-36 electrically or mechanically closed, the accumulators A and B are connected to opposite ends of one mill, and the accumulators C and D are connected to opposite ends of the other mill. By opening the valve 31 each of the accumulators A and B will act on both ends of one mill, and by opening valve 32, each of the accumulators C and D will act on both ends of the other mill. These are emergency valves, and normally closed. By opening valves 33, 34, 35 and 36, or the desired one of them, liquid will be delivered from the pump 39 to establish any desired pres-

sure on any one or all of the accumulators and rams simultaneously.

When accumulators A, B, C and D are hydraulically charged by the pump 39 to the desired pressure, valves 33, 34, 35 and 36 are electrically or manually closed, thus providing a closed hydraulic circuit between the accumulators and the rams. To create a greater pressure on the rams at the geared ends of the mills, liquid may be pumped in through a pipe 38 from a pump 39 driven by a motor 40. By opening the valve 41 and any one or all of the valves 33, 34, 35 and 36, liquid may be discharged from the accumulators, or the desired one of them, and returned through pipe 42 to a tank 43, from which the pump 39 draws its supply through a pipe 44 and filter 45. By opening a valve 46 liquid may be transferred from the spare accumulator E to the desired one of the other accumulators.

In case of bag rupture or any other failure of one of the accumulators A, B, C or D, the liquid may be drained from that one and from accumulator E, and the latter removed and substituted for the defective one. The building up of an undesirably high pressure in the accumulators and the rams being charged may be prevented by an automatic relief valve 47. It will be understood that when an accumulator is to be removed for any purpose, the liquid is drained out until the bag expands to close the check valve 25 and another accumulator is secured in place and the pressure raised by pumping in more liquid. Suitable pressure gauges are connected to the rams or the pipes leading to them, so that the desired higher pressure on the geared end of the mill may be obtained by pumping additional liquid into the accumulator connected to those ends. When operating the rams, no safety or relief valve is required on the accumulators on the rams, as the liquid and gas displacement of the accumulators is several times the liquid displacement in the ram cylinder 16.

It will be understood that in a simplified embodiment of my invention all of the piping, the pump and the reservoir may be omitted, and the threaded nipples 26' of the accumulators may be screwed into ram cylinders 16' when the upper roll 12 is in its lowermost position and the cylinder of the ram later filled with the pressure-transmitting liquid by means of a suitable hydraulic pump. The spare accumulator may be used to supply hydraulic pressure to other parts or apparatus in the factory, as it has a separate valve controlled pipe 49.

The piping for the pressure gauge and for conducting the liquid to the ram cylinder may be attached directly to the nipple as shown in Fig. 3, or may be branched from a pipe or tube secured to the end of the nipple 26 as indicated in Fig. 1.

By reason of the relatively large volume of the air on one side of the diaphragm or bag wall, and the high pressure on it, any slight leakage of the

oil or other liquid from the system will be compensated for by slight expansion of the bag, which does not materially reduce the pressure, or additional liquid may be pumped in from time to time to reduce the size of the bag and restore the pressure desired. The operator may thus increase or decrease the pressure on either or both ends of the mill at any time by pumping in or bleeding off liquid from the accumulator.

10 In my improved system, no safety valves or packings are required, and the spare accumulator may be quickly removed and substituted for any one of the others which may develop any trouble. The pump need be used only at rare intervals, and 15 when operating, its pulsations are cushioned by the high pressure gas.

Having thus described my invention what I claim as new and desire to secure by Letters Patent is:

A sugar cane roll mill having a pair of rolls rotatable about fixed axes and a superposed floating roll, said rolls being connected by gears at one end only thereof, means for rotating one of said pair of rolls and thereby rotating the other two through said gears, a pair of vertically movable bearings for the ends of said third roll, each bearing connected to a piston, a cylinder for each piston, and means for maintaining substantially constant pressure on both of said pistons, said 20 means including a pair of casings each having a flexible diaphragm with gas under high pressure at one side thereof and a liquid on the other side thereof, each liquid side of the casings of said pair being individual to and connected with one 25 of said cylinders, whereby upward movement of the ends of said superposed floating roll is resisted by substantially constant gas pressure through the medium of the pressure liquid separated from said gas under pressure by said flexible diaphragm, where 30 by said superposed floating roll is maintained under substantially constant and substantially equal pressure at its ends, notwithstanding the upward thrust exerted by said gears and the changing thickness of the mat of sugar cane passing through said rolls while said mill is running.
